United States Patent Office

Des. 178,597
Patented Aug. 28, 1956

178,597

TIME STAMP CASE OR SIMILAR ARTICLE

Benjamin Cooper, Brooklyn, N. Y.

Application December 13, 1955, Serial No. 39,323

Term of patent 14 years

(Cl. D64—11)

FIG. 1.

FIG. 2.

FIG. 3.

The back of the time stamp is plain and the opposite side of Fig. 3 is similar in appearance to Fig. 3.

I claim:

The ornamental design for a time stamp case or similar article, substantially as shown and described.
